MAINTAINED PRESSURE SNAP SWITCH

Raymond Reger, Anderson, Ind., assignor to The
Pierce Governor Company, Inc., Anderson, Ind.,
a corporation

Application September 8, 1947, Serial No. 772,715

10 Claims. (Cl. 74—97)

1

This invention relates to a snap action control mechanism.

The chief object of the present invention is to provide a control mechanism that is of snap action type and one wherein the actuating force may be of progressive character but wherein the control is shifted substantially instantaneously accompanied by pressure maintenance up to the instant of shifting and is reversely established immediately after shifting.

Herein the force applying member is of the to and fro movable type, one form being reciprocable and another oscillatable and one form being manually operable and another power operable and the same is given by way of example only.

The chief feature of the present invention resides in providing two pairs of spaced abutments and disposing therebetween in bridging relation an intermediately articulated structure, the control power being applicable thereto between the ends of said structure.

For purposes of illustration the control mechanism is disclosed as of switch type and the power operable forms thereof are disclosed as of centrifugal governor actuatable character.

Other objects and features of the invention will be set forth more fully hereinafter.

The full nature of the invention will be understood from the accompanying drawings and the following description and claims.

In the drawings, Fig. 1 is an elevational view of a centrifugal governor and switch structure controlled thereby, same embodying the invention, the cover for switch structure being omitted, the switch parts being illustrated in what might be termed the normal position.

Fig. 2 is a similar view of the same with parts illustrated in what might be termed the tripped position.

Fig. 3 is a similar view of a modified form of switch structure with parts in the so-called normal position.

Fig. 4 is a similar view of said modified form of the invention with parts in the so-called tripped position.

Fig. 5 is an elevational view of a manually operable switch embodiment of the invention, the cover being removed for clearness.

Fig. 6 is a transverse sectional view taken on line 6—6 of Fig. 5 and in the direction of the arrows.

Fig. 7 is a longitudinal sectional view taken on line 7—7 of Fig. 5 and in the direction of the arrows.

In Figs. 1 and 2 of the drawings, 10 indicates a governor housing to which is suitably secured base 11. Within such housing is disposed a conventional speed responsive structure comprising flyballs or weights rotatable by member 12 projecting from the housing and at a speed proportional to the speed of the unit to be controlled if the control mechanism is to be utilized for such purposes.

10 Shaft 13 projects beyond the base 11 and mounts arm 14. This shaft is moved counter-clockwise by the aforesaid weights when the rotational speed thereof is sufficient to generate sufficient centrifugal force to rock the shaft in opposition to spring 15 having one end secured to arm extension 16 and the other end adjustably anchored.

This adjustable anchorage may partake of many forms. Herein, for example, it comprises 20 an angle member 17 secured as at 18 to the base and adjustably supporting as at 19 a threaded member 20 having eye 21 for the other end of said spring. Lock nuts 22 secured said member in adjusted position and thus determine the force 25 of spring 15 which is to be overcome.

In the centrifugal governor art this spring is commonly termed the load spring and shaft 13 which partakes of oscillatory movement is commonly termed the rocker shaft.

For electrically operable transmission control purpose the speed governor described makes or breaks a control circuit at one critical speed and breaks or makes respectively a circuit at another speed corresponding to speed increase or decrease above or below governed speed.

The two limits are not necessarily the same. Normally centrifugal governors hunt or surge. To avoid repetitious reversible control at the so-called governor speed, the snap action of the 40 mechanism now to be described is peculiarly desirable in that positive selective control is effected at all times and maintained except at the instant of shift, as hereinafter pointed out more specifically.

The arm 14 aforesaid has secured to it at 23 an angular actuator member 24 with the free end 25 longitudinally slotted at 26 and transversely grooved as at 27 to form seats or pivots. Disposed in the slot 26 is the wire 28 hooked at 29 to one end of spring 30, the other end of which is hooked at 31 to one end of wire 32.

A metallic strap 33 is secured at 34 to base 11. At one end the strap terminates in spaced ears 35 which adjustably support stops 36 in the form of screws. These constitute one pair of

spaced abutments. Disposed therebetween and bearable upon one or the other of said abutments is strap 37 to which at 38 is secured or hooked the other end of wire 28. One end of said strap 37 is slotted and the legs seat in the seats 27 aforesaid.

The other end of strap 33 terminates in transverse end 39 apertured at 40 to accommodate tension wire 32. The remote face of end 39 is notched at 41 to form seats for the slotted adjacent end of strap 42 to which, remote from its seated end, as at 43, is anchored the other end of said wire 32.

Carried by base 11 are two aligned members 44 with spaced parallel ears 45 constituting a second pair of spaced abutments and between which the other end of strap member 42 is disposed, the latter bearing upon one or the other of said ears 45.

When the aforesaid is incorporated in a switch structure all or part of the aforesaid snap action mechanism, including arm 39, may be insulated. Herein terminal 46 is provided to the aforesaid articulated structure and terminal 47 is provided to one of the ears 45. Member 42 at the end between the ears 45 mounts contact 48.

In normal position (see Fig. 1) speed is insufficient to overcome spring 15; hence, the circuit is open between terminals 46 and 47 at contact 48. When the speed is sufficient to rock shaft 13 counterclockwise in opposition to spring 15, the switch assumes the tripped position, see Fig. 2, wherein the terminals 46-47 are now short circuited to complete the control circuit.

When selective dual circuit control is desired another terminal may be provided to the other of members 44. Then arm 42 at 48 selectively short circuits terminal 46 to the terminals on members 44. Fig. 5, incidentally, illustrates such a dual selective or tertiary control circuit arrangement.

It will be noted in Fig. 1 the elongated intermediate articulated and tensioned bridging structure bears at opposite ends upon the lower abutment of each pair of abutments while in Fig. 2, the bearing is upon the upper abutment of each pair of abutments.

The free ends of such bridging structure slide, as it were, upon the abutments until the articulating or breaking force is sufficient to effect the transfer. Pressure upon the abutments is maintained until the instant the break occurs and is immediately reestablished after the break occurs.

A modified form of the aforesaid is illustrated in Figs. 3 and 4. In this form the bridging structure is simplified and the load spring as well as the lever arm between same and the rocker shaft is adjustable. None of the abutments in this form is adjustable.

Herein abutments 136 comprise pins with insulation sleeves and same are carried by base 111. Rocker shaft 113 mounts arm 114 which carries threaded extension 116. Thereon is adjustably mounted sleeve 116^a and retained by opposed nuts 116^b. Load spring 115 connects at one end to the sleeve as shown and at the other end to eye 121 on threaded member 120 locked by nuts 122 to the housing wall 111^a on the base 111.

Herein spring 130 has elongated ends 128 and 132 connected at 138 and 143 respectively to strap members 137 and 142 respectively. The angular arm 124 has end 125 notched for seats

127 and slotted as at 126. Transverse member 139 is slotted at 140 and notched for seating strap member 142.

The two spaced abutments 145 are connected as follows: The lower one is electrically connected to terminal 146. This obviously completes the circuit to member 142. The upper abutment 145 insulatably supports contact 145^a electrically connected to terminal 147. Members 37 and 42 and 137 and 142 are longitudinally slotted adjacent their fulcrum ends. Such is shown more clearly in Fig. 7 relative to comparable members 237 and 242.

Operation of the form of the invention shown in Figs. 3 and 4 is substantially the same as that previously described. Note that in the first form the rocker shaft axis is to one side of both fulcrums whereas in the second form the rocker shaft axis is disposed between the fulcrums. The first form overall is longer but narrower than the second form. Either may be more advantageously utilized in special installations.

Reference will now be had to Figs. 5 to 7, inclusive wherein a most compact form is illustrated. Herein base 211 is defined by walls 211^a forming a switch chamber 211^b. A cover 210 completes the housing. One end wall is thickened at 209 and centrally notched at 209^a. Seated in the confronting walls of said notch are contacts 245 carried by pins 246 extending to the exterior and mounting terminals 247.

At the opposite end of the chamber and at the junction of that end wall with the side walls are the other pair of spaced abutments 236. Strap members 237 and 242 are connected at 238 and 243 respectively to opposite elongated ends 228 and 232 respectively of the spring 230.

Slidably supported in aligned slots 210^a is the reciprocatory member 225 having elongated slot 226 therein and angular or V-offset portion 227, same serving as a seat or fulcrum for the longitudinally slotted member 237. The slot therein and slot 226 accommodate the spring end 228.

Exteriorly of the housing is terminal 246 and pin or rivet 233 secures the same to the housing as well as angular member 239 notched at 240 and V-formed at 241 to seat or fulcrum the adjacent end of the longitudinally slotted member 242.

In this form dual selective or tertiary control is provided for. In this form the power application is reciprocatory instead of oscillatory. It also is applied substantially transverse to the bridging structure, and like the other forms the power is applied through one fulcrum providing member. As before the bridging structure contacts either the upper or the lower pairs of the abutments, see Fig. 5. The operation of this form is substantially like that previously described.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. Mechanism suitable for valve and switch control purposes comprising in combination a pair of spaced abutments, a second pair of spaced abutments, the two pairs being spaced apart, an elongated multiple pair of bridging type articu-

lated spring structures having substantially free ends disposed between the respective pairs of abutments and comprising a pair of longitudinally disposed abutment contacting elements, a force applying member associated with the said spring structure between the ends thereof for shifting the ends thereof for control purposes, a pair of fulcrums for the adjacent ends of said elements and having a tension connection between said elements, one of said fulcrums being stationary and the other being movable by the force applying member and in a direction generally transversely of the direction of elongation of said spring structure.

2. Mechanism as defined by claim 1 wherein the said adjacent ends are spaced apart.

3. Mechanism as defined by claim 2 wherein the force applying member is mounted for to and fro movement and to one side of said adjacent ends.

4. Mechanism as defined by claim 2 wherein the force applying member is mounted for to and fro movement and between said adjacent ends.

5. Mechanism as defined by claim 2 wherein the force applying member is mounted for to and fro movement and coincident with one of said adjacent ends.

6. Mechanism as defined by claim 1 wherein the force applying member includes a fulcrum providing portion for one of said elements.

7. Mechanism as defined by claim 6 wherein the force applying member is movable by centrifugal force in one direction through a lever arm responsive to such force and a spring constrains that lever arm toward the other direction.

8. Mechanism as defined by claim 7 wherein an adjustable support is provided for one end of the spring for adjusting the force thereof.

9. Mechanism as defined by claim 7 wherein 10 an adjustable connection is interposed between the lever arm and spring for adjusting the leverage of said arm.

10. Mechanism as defined by claim 7 wherein 15 an adjustable connection is interposed between the lever arm and one end of the spring for leverage adjustment and an adjustable anchorage is provided for the other end of the spring for spring force adjustment.
